[57] ABSTRACT

A horizontally-flexible rail which comprises rail pieces and connecting plates connecting the rail pieces together, the rail pieces being in contact with each other, each connecting plate being fixed to one of adjacent rail pieces, and pivotally connected to the other rail piece, the rail pieces, together with the connecting plates fixed thereto, being capable of horizontal arcing motion relative to adjacent rail pieces, the connecting plates serving to limit the arcing motions to a relatively small range.

HORIZONTALLY FLEXIBLE RAIL

FIELD OF THE INVENTION

This invention relates to flexible rails, flexible conveyors, and single-line parts coating systems.

BACKGROUND OF THE INVENTION

In a parts coating system, a conveyor chain from which trolleys are suspended is moved on rails. Works, such as automobile parts or electrical parts, to be coated with paint are suspended from the trolleys. Where works are relatively small and lightweight, the rail has a rectangular vertical cross section or a C-shaped cross section, for example. Where works are relatively large or heavy in weight, an I-shaped or H-shaped rail, for example, is used. A chain with rollers or a universal chain, for example, may be used as the conveyor chain. Where the trolleys must move in a curved path, a curved rail is used.

The rails (including curved rails), the chain and the trolleys thus comprise a single coating line or loop. Coating booths are located along the coating line. In each coating booth, paint of a particular color is provided (e.g., by spraying). Thus, if three coating booths are provided along the coating line, the coating line can coat three different kinds of parts with three different colors or can coat one part with three different colors. In actuality, however, it is impossible or difficult to provide more than 3 or 4 coating booths along one coating line. Thus, if such a large number of coating booths must be used, it is necessary to provide an additional coating line. If more than one coating line is provided, one of the coating lines is used according to the particular color of paint with which to paint the particular works.

However, it is possible to reduce the necessary number of coating lines by employing a "flexible rail" of the invention which will be hereinafter described in detail. For example, if two coating lines are required to provide six coating booths in the prior art, the "flexible rail" of the invention can be used to reduce the number of coating lines to one while providing the same number of coating booths.

SUMMARY OF THE INVENTION

It is an object of the invention to provide a horizontally-flexible rail.

Another object of the invention is to provide a horizontally-flexible rail which can be used to provide a single-line parts coating system.

Still another object of the invention is to provide a flexible conveyor.

A further object of the invention is to provide a single-line parts coating system using horizontally-flexible rails.

A horizontally-flexible rail according to the invention comprises rail pieces and connecting plates. The rail pieces are in contact with each other. Each intermediate rail piece has a concave front end face and a convex rear end face, and is in contact with adjacent rail pieces at its concave front end face and its convex rear end face, respectively. A foremost rail piece has a straight or flat front end face and a convex rear end face and, is in contact with the adjacent rail piece at its convex rear end face. A rearmost rail piece has a concave front end face and a straight or flat rear end face, and is in contact with the adjacent rail piece at its concave front end

face. Each of the connecting plates except the foremost one bridges adjacent rail pieces, and is fixed on the top of the rear one of the adjacent rail pieces. The foremost connecting plate is fixed on the top of the foremost rail piece. Each of the connecting plates except the foremost one is pivotally connected to the front one of the adjacent rail pieces. Thus, the each of the connecting plates except the foremost one can move in an arc (in a horizontal plane) together with the rail piece to which the connecting plate is fixed.

According to one aspect of the invention, the connecting plates are slightly spaced apart from each other, and each connecting plate has a trapezoidal front end with a central straight face and inclined side faces and a straight rear end. One of the inclined faces of the rear one of adjacent connecting plates and the straight rear end of the front connecting plate limit the arcing motions of the adjacent rail pieces to a small range.

According to another aspect of the invention, each connecting plate has a ridged front end with inclined faces which form a central ridge and a ridged rear end with inclined faces which form a central ridge, and the connecting plates are in contact with each other at the central ridges thereof,

A rail piece with a desired shape may be used. For example, an I-shaped rail piece may be used. A rail piece with other shape, such as the shape of the letter "C", can also be used.

A flexible conveyor according to the invention may comprise a single continuous central nonflexible rail which is movable, a first single continuous outer nonflexible rail, a second single continuous outer nonflexible rail, a first horizontally-flexible rail connected between the first outer nonflexible rail and the central nonflexible rail, a second horizontally-flexible rail connected between the central nonflexible rail and the second outer nonflexible rail, lateral guide rails for suspending the central nonflexible rail, lateral guide rails for suspending the flexible rail, trolleys which run suspended from the nonflexible and flexible rails, and means for moving the central nonflexible rail transversely in a horizontal plane.

A single-line parts coating system according to the invention may comprise plural coating sections each housing plural coating booths, movable nonflexible rails located in the respective coating sections, a first fixed nonflexible rail for introducing parts to be coated into a first coating section, intermediate fixed nonflexible rails located between the coating sections, a last fixed nonflexible rail for discharging the parts from a last coating section, horizontally-flexible rails located between the nonflexible rails to connect the nonflexible rails, means for suspending the movable nonflexible rail, means for suspending the horizontally-flexible rail, trolleys which run suspended from the nonflexible and flexible rails, and plural operating means each provided in conjunction with one of the coating sections for moving the movable nonflexible rail transversely in a horizontal plane to selectively locate the nonflexible rail in one of the coating booths.

BRIEF DESCRIPTION OF THE DRAWING

FIG. 1 is a perspective view of a flexible rail according to the invention;

FIG. 2 is a plan view of the flexible rail of FIG. 1;

FIG. 3 is a side view of the flexible rail of FIG. 1;

FIG. 4 shows a rail piece used in the flexible rail of FIG. 1;

In FIG. 5 the flexible rail of FIG. is suspended from a short rail member which is in turn suspended from a lateral rail;

FIG. 6 shows an intermediate rail piece and a connecting plate fixed thereto;

FIG. 7 shows a foremost rail piece and a connecting plate fixed thereto;

FIG. 8 shows a rearmost rail piece and a connecting plate fixed thereto;

FIG. 9 is a plan view of the flexible rail of FIG. 1 which shows how the flexible rail flexes;

In FIG. 10 two units of the flexible rail are used to provide a flexible conveyor. One flexible rail F1 is connected between an outer fixed nonflexible rail K₁ and a central transversely-movable nonflexible rail K₂, while another flexible F1 rail is connected between the central nonflexible rail K₂ and an outer fixed nonflexible rail K₃. Thus, as illustrated, when the central nonflexible rail K₂ is moved transversely (in a horizontal plane), the flexible rails F1 concomitantly flex, or make a wavy motion, in a horizontal plane;

FIG. 11 shows a rail piece and a connecting plate which may be used instead of the rail piece and the connecting plate used for the flexible rail of FIG. 1;

FIG. 12 shows a flexible rail constructed by using the flexible rail and the connecting plate of FIG. 11;

FIG. 13 is a front view of the rail piece and the connecting plate of FIG. 11;

FIGS. 14, 15 and 16 show different rail pieces;

FIG. 17 shows a flexible conveyor according to the invention;

FIG. 18 is a plan view of the flexible conveyor of FIG. 17; and

FIG. 19 is a plan view of a single-line parts coating system according to the invention.

DETAILED DESCRIPTION OF PREFERRED EMBODIMENTS

First Flexible Rail

A flexible rail F1 which embodies the invention in one preferred form will now be described in detail with reference to FIGS. 1 to 10.

Referring to FIGS. 1, 2 and 3 in particular, the flexible rail F1 comprises generally I-shaped rail pieces R₀ to R_n and horizontal connecting plates S₁ to S_n.

All the rail pieces except the extreme ones R₀ and R_n, namely the intermediate rail pieces R₁ to R_{n-1}, have identical shapes.

FIG. 6 depicts one of the intermediate rail pieces. As depicted, the intermediate rail piece generally has the shape of the letter "I", and has a concave front end face 5 and a convex rear end face 4.

FIG. 7 depicts one of the extreme rail pieces, namely, a foremost rail piece R₀. As depicted, the foremost rail piece has a shape identical to that of the intermediate rail piece except that the foremost rail piece has a flat or straight front end face 6.

FIG. 8 depicts the other extreme rail piece, namely, a rearmost rail piece R_n. As depicted, the rearmost rail piece has a shape identical to that of the intermediate rail piece except that the rearmost rail piece has a flat or straight rear end face 7.

In FIG. 4, reference numeral 1 designates a horizontal top portion of the rail piece (R₀ to R_n); reference numeral 3, a vertical intermediate portion thereof; and

reference numeral 2, a horizontal bottom portion thereof.

In FIG. 6, reference numeral 4A designates a top portion of the convex rear end face 4; reference numeral 4C, a vertical portion thereof; and reference numeral 4B, a bottom portion thereof. Also, in FIG. 6, reference numeral 5A designates a top portion of the convex front end face 5; reference numeral 5C, a vertical portion thereof; and reference numeral 5B, a bottom portion thereof.

The rail pieces are connected together by horizontal connecting plates S₁ to S_n.

The connecting plate S₁ connects the first rail piece R₀ (foremost rail piece) and the second rail piece R₁.

15 The connecting plate S_n connects the last rail piece R_n (rearmost rail piece) and the rail piece located immediately in front of the last rail piece R_n.

Each of the connecting plates (S₁ to S_n) except the foremost one S₀ bridges adjacent rail pieces, and is fixed to 20 the rear one of the adjacent rail pieces (FIG. 13).

Each connecting plate is provided with a pair of opposed rear openings 11, and the top portion 1 of each rail piece is provided with opposed front openings 9 which are vertically aligned with the respective rear openings 11 of the connecting plate. Bolts 14 and nuts 15 may be used to fix the connecting plate to the rail piece. That is, the bolts 14 may be inserted into the openings 11 and 19 and received by the nuts 15 (FIG. 3). However, not all the connecting plates are fixed to the 30 rail pieces in such a manner. That is, it is necessary to fix some of the connecting plates to the rail pieces by means of long bolts 16 (FIGS. 1, 3, 4 and 6). As clearly shown in FIG. 6, the long bolts 16 are also inserted into the openings 11 and 9. An upper nut 17 and a lower nut 35 18 are used in conjunction with the long bolt 16.

The reason for the necessity to fix some of the connecting plates in such manner is that it is necessary to suspend the flexible rail F1 in use. For this purpose, the top of the long bolt 16 has an opening 19 (FIGS. 4 and 40 6). If desired, however, the top of the long bolt 16 may be made into the shape of a hook for the same purpose (not shown).

All the connecting plates except the foremost one S₀ have identical shapes. That is, each connecting plate 45 (S₁ to S_n) has a central straight face 23 and inclined side faces 24, 24 at its front end, and has a straight rear end 22 (FIGS. 6 and 8). Also, the bottom of each connecting plate (S₁ to S_n) has a recess 12 with a curved rear face 13 (FIGS. 3, 6 and 8). The rear curved face 13 corresponds to the concave front end face 5 of the rail piece. To be more exact, the curved rear face 13 is vertically aligned with the concave front end face 5 of the rail piece.

The foremost connecting plate S₀ has exactly the 55 same shape as each of the other connecting plates (S₁ to S_n) except that the foremost connecting plate S₀ has no recess at its bottom (FIGS. 3 and 7).

Each connecting plate has a front central opening 10 (FIGS. 1, 6, 7 and 8). Each of the rail pieces except the 60 rearmost one R_n has a threaded opening 8 which is vertically aligned with the front central opening 10 (FIGS. 6 and 7). The opening 8 is located at a substantial middle of the length direction of the top 1 of the rail piece. A bolt (P₁ to P_n) is screwed into the openings 10 and 8. The bolt has a thread at its lower portion, and the thread of the bolt is engaged with the thread of the opening 8. Thus, the bolt is fixed to the rail piece. Hence 65 the bolt serves to connect adjacent rail pieces together.

For example, a bolt P_1 (FIGS. 2 and 3) serves to connect the first rail piece R_0 (foremost rail piece) and the second rail piece R_1 together. Similarly, a bolt P_3 serves to connect the rail pieces R_2 and R_3 together. A rearmost bolt P_n serves to connect the last two rail pieces R_n and R_{n-1} together.

However, the bolt (P_1 to P_n) is not fixed to the connecting plate, but the bolt is rotatable in the opening 10 of the connecting plate. To be exact, the bolt and the rail piece (to which the bolt is fixed), as one body, are capable of arcing motion relative to the connecting plate in a horizontal plane. To be more exact, each of adjacent rail pieces, together with the connecting plate fixed thereto, is capable of horizontal arcing motion relative to the other rail piece.

Thus, each bolt (P_1 to P_n) may be called a "pivotal bolt".

Adjacent rail pieces are in contact with each other. That is, the concave front end face 5 of the rear one of adjacent rail pieces is in contact with the convex rear end face 4 of the front rail piece.

As shown in FIG. 2, adjacent connecting plates are not in contact with each other, but have a small space e between them. To be exact, the straight rear end 22 of the front one of adjacent connecting plates is spaced apart for the small distance e from the central straight face 23 of the front end of the rear connecting plate.

Each of the side faces 24 of the front end of the connecting plate is inclined at an angle of 4 or 5 degrees (FIG. 6). This angle is designated by the letter θ .

As described above, the rail piece and the connecting plate fixed thereto, as one body, are capable of arcing motion in a horizontal plane and, hence, constitute an "arcing unit". Shortly after starting to arc, however, the rear arcing unit is stopped by the front arcing unit, since one of the inclined side faces 24 of the connecting plate of the rear arcing unit engages with the straight rear end 22 of the connecting plate of the front arcing unit. In other words, the connecting plates of the arcing units limit the arcing motions thereof to small ranges by engaging with each other.

In FIGS. 1 and 2 the line H—H is a longitudinal centerline of the flexible rail F1. The centerline H—H connects the centers of the threaded openings 8 of the rail pieces. As described before, the pivotal bolt (P_1 to P_n) is inserted into the openings 10 and 8. As may be understood from FIG. 2, the convex rear end face 4 of the foremost rail piece R_0 coincides with a curved line produced by drawing a circle with the radius X round the center of the threaded opening 8 into which the pivotal bolt P_1 is screwed. The concave front end face 5 of the second rail piece R_1 also coincides with the above-mentioned curved line. Similarly, although not shown, the convex rear end face 4 of the second rail piece R_1 , as well as the concave front end face 5 of the third rail piece R_2 , coincides with a curved line produced by drawing a circle with the radius X round the center of the opening 8 into which the pivotal bolt P_2 is screwed. Also, the convex rear end face 4 of the rail piece R_{n-1} , as well as the concave front end face 5 of the rearmost rail piece R_n , coincides with a curved line produced by drawing a circle with the radius X round the center of the opening 8 into which the pivotal bolt P_n is screwed.

In short, the convex rear end face 4 of the front one of adjacent rail pieces and the concave front end face 5 of the rear rail piece coincide with a curved line produced by drawing a circle with the radius X round the

center of the threaded opening 8 into which the pivotal bolt connecting the adjacent rail pieces is screwed.

The foremost rail piece R_0 may be connected to a non-flexible rail K_1 at its flat front end face 6 (FIGS. 2 and 7). Similarly, the rearmost rail piece R_n may be connected to a non-flexible rail K_2 at its flat rear end face 7 (FIGS. 2 and 8).

As shown in FIG. 3, a washer 21 is disposed in the bottom recess of each connecting plate (S_1 to S_n). That is, the washer 21 is located between the opening 10 of the connecting plate and the threaded opening 8 of the rail piece. The pivotal bolt is inserted through the washer 21 into the threaded opening 8.

As described before, some of the connecting plates are fixed to the rail pieces by means of the long bolts 16 (FIGS. 1, 3, 4 and 6). As indicated by reference numeral 20 of FIG. 4, it may be desirable that the connecting plate fixed to the rail piece by the long bolts 16 be welded to the rail piece for firmer fixation.

In use the flexible rail F1 may be suspended as shown in FIG. 5. In FIG. 5 a trolley T is carried on the flexible rail F1. Reference numeral 42 designates guide rollers of the trolley T which rest on the bottom of the flexible rail F1.

The flexible rail F1 can be effectively used for conveyance of relatively large or heavy objects.

Action of the Flexible Rail

The construction of the flexible rail F1 is as described above.

As described above and as shown in FIG. 9, the foremost rail piece R_0 and the rearmost rail piece R_n may be connected (fixed) to nonflexible rails K_1 and K_2 , respectively. FIG. 9 shows two possible flexures of the flexible rail F1. In FIG. 9 the nonflexible rail K_1 or K_2 is moved in a horizontal plane while the other nonflexible rail (K_1 or K_2) is fixed. As shown, when the nonflexible rail (K_1 or K_2) is moved, the flexible rail F1 flexes, or makes a wavy motion, in a horizontal plane.

In FIG. 9, each of the rail pieces nearer to the nonflexible rail K_1 or K_2 (except the foremost and rearmost rail pieces R_0 and R_n) is stopped shortly after starting to arc, since the adjacent connecting plates engage with each other at one of the inclined side faces 24 (of one of the adjacent connecting plates) and the straight rear end 22 (of the other connecting plate). In FIG. 9, however, the central connecting plates are not in contact with each other, but is slightly spaced from each other and, hence, the central rail pieces move in smaller arcs than the rail pieces nearer to the nonflexible rails.

In FIG. 10, one flexible rail F1 is connected to an immovable rail K_1 at the forward end thereof and to a central horizontally movable rail K_2 at the rearward end thereof. Also, another flexible rail F1 is connected to the central movable rail K_2 at the forward end thereof and to an immovable rail K_3 at the rearward end thereof. Thus, if the central movable rail K_2 is moved as illustrated, the two flexible rails F1 flex in a horizontal plane as illustrated.

Second Flexible Rail

A flexible rail F2 which embodies the invention in another preferred form will now be described in detail with reference to FIGS. 11 to 13. Parts of the flexible rail F2 similar to those of the flexible rail F1 are designated by the same reference numerals.

The flexible rail F2 comprises rectangular hollow rail pieces R₀ to R_n and horizontal connecting plates S₁ to S_n.

As with the first embodiment, all the rail pieces except the extreme ones R₀ and R_n, namely the intermediate rail pieces R₁ to R_{n-1}, have identical shapes.

FIG. 11 depicts one of the intermediate rail pieces. As depicted, the intermediate rail piece has a rectangular hollow shape, and has opposed bottom lips 27 which are spaced apart from each other. As with the first embodiment, the intermediate rail piece has a concave front end face 29 and a convex rear end face 28.

As with the first embodiment, although not shown, the foremost rail piece R₀ has a shape identical to that of the intermediate rail piece except that the foremost rail piece R₀ has a flat or straight front end face. Also, although not shown, the rearmost rail piece R_n has a shape identical to that of the intermediate rail piece except that the rearmost rail piece R_n has a flat or straight rear end face.

The rail pieces are connected together by horizontal connecting plates S₁ to S_n. All the connecting plates have identical shapes except that the foremost connecting plate S₀ (not shown) has no bottom recess.

As described before, the connecting plate of the flexible rail F1 has an angular front end and a straight rear end 22. However, as illustrated in FIG. 11, the connecting plate of the flexible rail F2 has ridged front and rear ends. That is, the front end of the connecting plate includes inclined faces 30, 30 which form a central ridge 30A. Similarly, the rear end of the connecting plate includes inclined faces 31, 31 which form a central ridge 31A. The inclined face inclines at an angle of 3 to 5 degrees. This angle is designated by the letter θ . Adjacent connecting plates are in contact with each other at the ridges 30A and 31A thereof.

The connecting plate is fixed to the rail piece by means of a short bolt 14 or a long bolt 16 which are inserted into an opening 11 of the connecting plate and an opening 9 of the rail piece. For the same reason as in the first embodiment, it is necessary to fix some of the connecting plates to the rail pieces by means of the long bolts 16.

A pivotal bolt (P₁ to P_n) is inserted into a front opening 10 of the connecting plate and an opening 8A of the rail piece and, thus, serves to connect adjacent rail pieces together. A nut 32 is used in conjunction with the bolt (P₁ to P_n). As with the first embodiment, the pivotal bolt is fixed to the rail piece, but is not fixed to the connecting plate. The pivotal bolt is rotatable in the opening 10. Thus, as with the first embodiment, the pivotal bolt and the rail piece (to which the pivotal bolt is fixed), as one body, are capable of horizontal arcing motion relative to the adjacent rail pieces.

The opening 8A of the rail piece is located at the middle of the length direction of the top of the rail piece. A longitudinal centerline H—H of the flexible rail F2 connects the centers of the openings 8A of the rail pieces.

As with the first embodiment, the convex rear end face 28 of the front one of adjacent rail pieces and the concave front end face 29 of the rear rail piece coincide with a curved line produced by drawing a circle with the radius X round the center of the opening 8A into which the pivotal bolt connecting the adjacent rail pieces is inserted.

As with the first embodiment, the rail piece and the connecting plate fixed thereto constitute an "arcing

unit". Shortly after starting to arc (in a horizontal plane), however, the rear arcing unit is stopped, since one of the front inclined faces 30 of the connecting plate thereof engages with the adjacent rear inclined face 31 of the connecting plate of the front arcing unit. That is, the connecting plates of the arcing units limit the arcing motions thereof to small ranges by engaging with each other.

Thus it will be appreciated that the flexible rail F2 also can flex as illustrated in FIGS. 9 and 10.

For example, a conveyor chain with side rollers or a universal chain can be carried on the flexible rail F2. The opposed bottom lips support the chain.

As described before, the flexible rail F1 can be effectively used for conveyance of relatively large or heavy objects. In contrast, the flexible rail F2 is particularly adapted for conveyance of relatively small or lightweight objects.

It will be appreciated that, if desired, a connecting plate with a shape similar to that of the connecting plate of the flexible rail F1, instead of the connecting plate of FIG. 11, may be used for the flexible rail F2. Similarly, if desired, a connecting plate with a shape similar to that of the connecting plate of FIG. 11 may be used for the flexible rail F1.

Variations of Rail Piece

A rail piece of FIG. 14 has substantially the same construction as the rail piece of FIGS. 11 to 13, except that the rail piece of FIG. 14 comprises an outer, large shell construction similar to the rail piece of FIGS. 11 to 13 and an inner, small shell construction having a shape similar to that of the outer shell construction. The inner shell construction is welded to the top of the outer shell construction as indicated at 33. A conveyor chain may be carried on (opposed bottom lips 27A of) the inner shell construction. A trolley may be carried on (opposed bottom lips 27 of) the outer shell construction.

FIG. 15 shows a generally C-shaped rail piece which can also be used to provide a flexible rail according to the invention. A pivotal bolt (P₁ to P_n) is located at the center of gravity of the rail piece. A chain conveyor can be carried on the rail as indicated by a dotted line.

FIG. 16 shows another rail piece which can be used to provide a flexible rail according to the invention. As illustrated, the rail piece of FIG. 16 comprises two generally C-shaped constructions welded together at 38. In manufacture of such a flexible rail, the bottom of a pivotal bolt (P₁ to P_n) is first welded to the rail piece as indicated by reference numeral 39, and then a connecting plate (S₁ to S_n) with an opening 10 is placed on the rail piece in such a manner that the pivotal bolt projects from the opening 10. Then, the head of the pivotal bolt is welded to the connecting plate as indicated by reference numeral 40.

Moreover, although not shown, an H-shaped rail piece can also be used to provide a flexible rail according to the invention.

All the above-mentioned rail pieces can be obtained by cutting commercially available shape steels. For example, a number of rail pieces of FIG. 1 can be obtained by cutting an I-steel. Also, a number of rail pieces of FIG. 11 can be obtained by cutting a lip channel steel. However, if desired, any one of the above-mentioned rail pieces can be provided individually. For example, a rail piece can be cast.

Flexible Conveyor

The flexible rails according to the invention can be used to provide a flexible conveyor. Such a flexible conveyor is generally illustrated in FIG. 10. FIGS. 17 and 18 illustrate such a flexible conveyor in detail.

FIGS. 17 and 18 must be viewed in conjunction with FIGS. 3 and 5 since details not illustrated in FIGS. 17 and 18 are illustrated in FIGS. 3 and 5.

In FIGS. 17 and 18 a flexible rail F1 is connected between a left-hand immovable I-shaped rail K1 and a central horizontally movable I-shaped rail K2, while another flexible rail F1 is connected between the central rail K2 and a right-hand immovable I-shaped rail K3. Each of the rails k1, k2 and K3 does not comprise plural rail pieces, but is a single continuous rail and, hence, is not flexible.

The letter D designates a framework.

As illustrated in FIG. 18, the central nonflexible rail K2 is movable in a lateral direction of the framework D.

The rail k1, located on a side of supply of works, is fixed to a left-hand lateral I-shaped rail 46. The rail k3, located on a side of discharge of works, is fixed to a right-hand lateral I-shaped rail 47.

Each of the flexible rails F1 is suspended from lateral I-shaped rails 48 fixed to the top of the framework D. That is, a trolley 54 is carried on the rail 48 with guide rollers 55 (of the trolley 54) supported on the bottom of the rail 48. An I-shaped rail member 53 is fixed to the lower end of the trolley 54. A trolley 56 is in turn carried on the rail member 53 with guide rollers 58 (of the trolley 56) supported on the bottom of the rail member 53. A hook 57 is rotatably connected to the lower end of the trolley 56 (FIG. 5). A suspending means 59 is suspended from the lower end of the hook 57 (FIG. 5). The bolts 16 of the flexible rail F1 is in turn suspended from the suspending means 59.

Lateral I-shaped rails 49 are located between the left-hand lateral rails 48 and the right-hand lateral rails 48. The central lateral rails 49 are also fixed to the top of the framework D. Trolleys 51 are carried on the central lateral rails 49 with guide rollers 52 (of the trolleys 51) supported on the bottoms of the central lateral rails 49. A rectangular frame 50 is in turn suspended from the trolleys 51. The central movable longitudinal rail K2 is fixed to the bottom of the frame 50.

Trolleys 41 are moved along the rails K1, F1, K2, F1 and K3, with guide rollers 42 (of the trolleys 41) supported on the bottoms of the rails.

In FIGS. 3 and 5 reference numeral 43 designate brackets which connect link chains 44. A hanger 45 is suspended from the trolley 41. A work W is in turn suspended from the hanger 45.

A motor support 60 is mounted on the frame 50. A motor M in turn mounted on the motor support 60. A driving shaft 61 is operatively connected to the motor M. The driving shaft 61 is supported on bearings 62. Driving sprockets 63 are connected to the ends of the driving shaft 61, respectively. Two guide sprockets 64 are located with each driving sprocket 63 between as viewed from above). The guide sprockets 64 are supported on bearings 65. A chain 66 is fitted on the driving sprocket 63 and the guide sprockets 64. One end 66A of the chain 66 is fixed to one side of the top of the framework D, while the other end 66B of the chain 66 is fixed to the opposed side of the top of the framework D.

Operation of the Flexible Conveyor

The construction of the flexible conveyor according to the invention is as described above.

In use, the motor M is operated. Thereupon, the driving shaft 61 and, hence, the driving sprockets 63 are rotated, so that the frame 50 and, hence, the central nonflexible rail K2 are moved toward one side of the framework D. This movement is guided by the guide rollers 52 rolling on the lateral rails 49. When the central nonflexible rail K2 is thus moved, the flexible rails F1 flex concomitantly (FIG. 18). The flexure of the flexible rail F1 is guided by the guide rollers 55 rolling on the lateral rail 48.

When the flexible rail F1 thus flexes, its rail pieces slightly move in a longitudinal direction, or in the direction in which the works W are conveyed. The guide rollers 58 allow for this longitudinal movement. That is, when the rail pieces thus move, the guide rollers 58 roll on the I-shaped member 53.

Parts Coating System

The flexible rails according to the invention can be used to provide a single-line parts coating system of FIG. 19.

The coating system of FIG. 19 includes a trolley conveyor T and coating sections D1, D2 and D3 located along the trolley conveyor T. Reference numeral 67 designates means for operating the trolley conveyor T. Reference numeral 68 designates a furnace for drying coated works by baking them. Coating booths E1 and E2 are located in the coating section D1; coating booths E3 and E4, in the coating section D2; and coating booths E5 and E6, in the coating section D3.

A nonflexible rail K2 is located in each coating section. The nonflexible rail K2 is movable in the lateral direction of the coating section.

An nonflexible rail K1 is located on the supply side of the coating section D1. Another nonflexible rail is located between the coating sections D1 and D2 (this rail is designated by both reference numerals K3 and K1). Another nonflexible rail is located between the coating sections D2 and D3 (this rail is also designated by both reference numerals K3 and K1). Another nonflexible rail K3 is located on the discharge side of the coating section D3. All these nonflexible rails located outside the coating sections are immovable.

As illustrated, all the nonflexible rails K1, k2 and K3 are connected to each other by flexible rails of the invention.

Each coating booth (E1 to E6) may be provided with devices, such as sprays, for coating works with paint of a particular color. Thus, the parts coating system of FIG. 19 can coat works with 6 different colors.

Operation of the Parts Coating System

In the foregoing parts coating system, works to be painted with particular colors, such as automobile parts or electrical parts, are loaded on the trolley conveyor T at, for example, 69. Then, the trolley conveyor T is moved. When the works have entered the coating section housing the coating booth where the paint with which to coat the works is provided, the conveyor T is stopped. Or immediately before the works enter the coating section, the conveyor T is stopped. Then, the nonflexible rail K2 is moved into the coating booth. If the conveyor T has been stopped immediately before the works enter the coating section, the trolley T is

restarted so that the works come into the coating booth. Then, the works are coated with the paint of the required color in the coating booth. Then, the nonflexible rail K_2 is returned to the middle position, and the works are conveyed to the drying furnace 68. Or the works are conveyed to the drying furnace 68 without returning the nonflexible rail k_2 to the middle position. Then, the works are unloaded at 70.

What is claimed is:

1. A flexible rail comprising

(i) rail pieces (R_0-R_n) which are in contact with each other,

intermediate ones (R_1-R_{n-1}) of the rail pieces each having a concave front end face and a convex rear end face and being in contact with adjacent rail pieces at its concave front end face and its convex rear end face, respectively,

a foremost one (R_0) of the rail pieces having a straight and flat front end face and a convex rear end face and being in contact with the adjacent rail piece (R_1) at its convex rear end face, and

a rearmost one (R_n) of the rail pieces having a concave front end face and a straight and flat rear end face and being in contact with the adjacent rail piece (R_{n-1}) at its concave front end face,

(ii) connecting plates (S_0-S_n) for connecting the rail pieces (R_0-R_n) together,

each of the connecting plates (S_1-S_n) except a foremost one (S_0) bridging adjacent rail pieces,

(iii) means for fixing each of the connecting plates (S_1-S_n) except the foremost connecting plate (S_0) on a top of one of adjacent rail pieces,

(iv) pivotal connecting means (P_1-P_n) located along a longitudinal centerline of the flexible rail for connecting each of the connecting plates (S_1-S_n) to the other one of the adjacent rail pieces such that the connecting plate, together with the rail piece to which the connecting plate is fixed, can move in an arc, in a horizontal plane, relative to the other one of the adjacent rail pieces, and

the pivotal connecting means thus connecting the adjacent rail pieces together for relative arcing motion,

(v) means for fixing the foremost connecting plate (S_0) on a top of the foremost rail piece (R_0),

(vi) arcing-motion limiting means for limiting the arcing motion of the connecting plate to a relatively small range,

(vii) the convex rear end face of each of the intermediate rail pieces (R_1-R_n) and the concave front end face of the adjacent rail piece which is in contact therewith, coinciding with a curved line produced by drawing a circle with a predetermined radius round a center of an opening of the rail piece into which the pivotal connecting means connecting the adjacent rail pieces together is inserted,

(viii) the convex rear end face of the foremost rail piece (R_0) and the concave front end face of the rail piece (R_1) located immediately behind the foremost rail piece (R_0), coinciding with a curved line produced by drawing a circle with a first given radius round a center of an opening of the foremost rail piece into which the pivotal connecting means connecting the foremost rail piece and the rail piece (R_1) together is inserted, and

said first given radius being equal to said predetermined radius, and

(ix) the concave front end face of the rearmost rail piece (R_n) and the convex rear end face of the rail piece (R_{n-1}) located immediately in front of the rearmost rail piece, coinciding with a curved line produced by drawing a circle with a second given radius round a center of an opening of the rail piece (R_{n-1}) into which the pivotal connecting means connecting the rearmost rail piece and the rail piece (R_{n-1}) together is inserted, and

said second given radius being equal to said predetermined radius.

2. A flexible rail in accordance with claim 1 wherein each of the rail pieces (R_0-R_n) is a generally I-shaped rail piece.

3. A flexible rail in accordance with claim 1 wherein each of the rail pieces (R_0-R_n) is a rectangular hollow rail piece with open front and rear ends and with opposed bottom lips which are spaced apart from each other.

4. A flexible rail in accordance with claim 1 wherein each of the rail pieces (R_0-R_n) comprises (a) a large rectangular hollow rail piece with open front and rear ends and with opposed bottom lips which are spaced apart from each other and (b) a small rail piece located inside the large rail piece and having a shape similar to that of the large rail piece, the small rail piece being fixed to a top of the large rail piece.

5. A flexible rail in accordance with claim 1 wherein each of the rail pieces (R_0-R_n) is a generally C-shaped rail piece.

6. A flexible rail in accordance with claim 1 wherein each of the rail pieces (R_0-R_n) comprises a pair of generally C-shaped rail pieces having vertical walls fixed together and facing in opposite directions.

7. A flexible rail in accordance with claim 1 wherein the connecting plates (S_0-S_n) are slightly spaced apart from each other, and each of the connecting plates (S_0-S_n) has a trapezoidal front end with a central straight face (23) and inclined side faces (24) and a straight rear end (22),

one of the inclined faces (24) of a rear one of adjacent connecting plates and the straight rear end (22) of a front one of the adjacent connecting plates providing said arcing-motion limiting means by engaging with each other.

8. A flexible rail in accordance with claim 2 wherein the connecting plates (S_0-S_n) are slightly spaced apart from each other, and each of the connecting plates (S_0-S_n) has a trapezoidal front end with a central straight face (23) and inclined side faces (24) and a straight rear end (22),

one of the inclined faces (24) of a rear one of adjacent connecting plates and the straight rear end (22) of a front one of the adjacent connecting plates providing said arcing-motion limiting means by engaging with each other.

9. A flexible rail in accordance with claim 3 wherein the connecting plates (S_0-S_n) are slightly spaced apart from each other, and each of the connecting plates (S_0-S_n) has a trapezoidal front end with a central straight face (23) and inclined side faces (24) and a straight rear end (22),

one of the inclined faces (24) of a rear one of adjacent connecting plates and the straight rear end (22) of a front one of the adjacent connecting plates providing said arcing-motion limiting means by engaging with each other.

10. A flexible rail in accordance with claim 4 wherein the connecting plates (S_0-S_n) are slightly spaced apart from each other, and each of the connecting plates (S_0-S_n) has a trapezoidal front end with a central straight face (23) and inclined side faces (24) and a straight rear end (22),

one of the inclined faces (24) of a rear one of adjacent connecting plates and the straight rear end (22) of a front one of the adjacent connecting plates providing said arcing-motion limiting means by engaging with each other. 10

11. A flexible rail in accordance with claim 7 wherein the connecting plates (S_0-S_n) are slightly spaced apart from each other, and each of the connecting plates (S_0-S_n) has a trapezoidal front end with a central straight face (23) and inclined side faces (24) and a straight rear end (22),

one of the inclined faces (24) of a rear one of adjacent connecting plates and the straight rear end (22) of a front one of the adjacent connecting plates providing said arcing-motion limiting means by engaging with each other. 15

12. A flexible rail in accordance with claim 6 wherein the connecting plates (S_0-S_n) are slightly spaced apart from each other, and each of the connecting plates (S_0-S_n) has a trapezoidal front end with a central straight face (23) and inclined side faces (24) and a straight rear end (22),

one of the inclined faces (24) of a rear one of adjacent connecting plates and the straight rear end (22) of a front one of the adjacent connecting plates providing said arcing-motion limiting means by engaging with each other. 20

13. A flexible rail in accordance with claim 1 wherein each of the connecting plates (S_0-S_n) has a ridged front end with inclined faces (30) which form a central ridge (30A) and a ridged rear end with inclined faces (31) which form a central ridge (31A), and the connecting plates (S_0-S_n) are in contact with each other at the central ridges (30A, 31A) thereof,

one of the inclined faces (30) of one of adjacent connecting plates and the opposed inclined face (31) of the other of the adjacent connecting plates providing said arcing-motion limiting means by engaging with each other. 35

14. A flexible rail in accordance with claim 2 wherein each of the connecting plates (S_0-S_n) has a ridged front end with inclined faces (30) which form a central ridge (30A) and a ridged rear end with inclined faces (31) which form a central ridge (31A), and the connecting plates (S_0-S_n) are in contact with each other at the central ridges (30A, 31A) thereof,

one of the inclined faces (30) of one of adjacent connecting plates and the opposed inclined face (31) of the other of the adjacent connecting plates provid- 50

5

ing said arcing-motion limiting means by engaging with each other.

15. A flexible rail in accordance with claim 3 wherein each of the connecting plates (S_0-S_n) has a ridged front end with inclined faces (30) which form a central ridge (30A) and a ridged rear end with inclined faces (31) which form a central ridge (31A), and the connecting plates (S_0-S_n) are in contact with each other at the central ridges (30A, 31A) thereof,

one of the inclined faces (30) of one of adjacent connecting plates and the opposed inclined face (31) of the other of the adjacent connecting plates providing said arcing-motion limiting means by engaging with each other. 10

16. A flexible rail in accordance with claim 4 wherein each of the connecting plates (S_0-S_n) has a ridged front end with inclined faces (30) which form a central ridge (30A) and a ridged rear end with inclined faces (31) which form a central ridge (31A), and the connecting plates (S_0-S_n) are in contact with each other at the central ridges (30A, 31A) thereof,

one of the inclined faces (30) of one of adjacent connecting plates and the opposed inclined face (31) of the other of the adjacent connecting plates providing said arcing-motion limiting means by engaging with each other. 15

17. A flexible rail in accordance with claim 5 wherein each of the connecting plates (S_0-S_n) has a ridged front end with inclined faces (30) which form a central ridge (30A) and a ridged rear end with inclined faces (31) which form a central ridge (31A), and the connecting plates (S_0-S_n) are in contact with each other at the central ridges (30A, 31A) thereof,

one of the inclined faces (30) of one of adjacent connecting plates and the opposed inclined face (31) of the other of the adjacent connecting plates providing said arcing-motion limiting means by engaging with each other. 20

18. A flexible rail in accordance with claim 6 wherein each of the connecting plates (S_0-S_n) has a ridged front end with inclined faces (30) which form a central ridge (30A) and a ridged rear end with inclined faces (31) which form a central ridge (31A), and the connecting plates (S_0-S_n) are in contact with each other at the central ridges (30A, 31A) thereof,

one of the inclined faces (30) of one of adjacent connecting plates and the opposed inclined face (31) of the other of the adjacent connecting plates providing said arcing-motion limiting means by engaging with each other. 25

19. A flexible rail of claim 1 further including means (16) for suspending the whole of the rail pieces connected together.
